4 Claims. (Cl. 38—66)

This invention is for improvements in or connected with laundry presses and has for one of its objects to improve the efficiency and simplify the construction of the pressure bucks. The invention is concerned with presses of the type in which the pressure bucks are heated by steam or other fluid.

According to the primary feature of the present invention, there is provided a pressure buck for a laundry press, comprising a wall one face of which is the pressure-applying face and the opposite face of which has a multi-channel-shaped member attached to it in such manner as, with the said wall, to form conduits for the passage of a fluid for heating the wall. Conveniently the said channel-shaped member is of corrugated sheet formation and the valleys of the corrugations are attached to said wall in such manner that between adjacent valleys there is a heating fluid conduit formed by the corrugation and the wall. It is preferred to have the ends of the conduits closed, and to have portions of the lengths of said valley spaced away from the wall to afford restricted communication between adjacent conduits. Thus the heating fluid can pass not only along the conduits but also between adjacent conduits. The valleys may be dimpled at intervals along their length and welded to the wall at the situations of the dimples, this arrangement ensuring that the valleys are adequately secured to the wall while affording communication between adjacent conduits.

For a more complete understanding of the invention there will now be described, by way of example only and with reference to the accompanying drawings, one constructional form of pressure buck according to the invention. It is to be understood, however, that the invention is not restricted to the precise constructional details set forth.

In these drawings:

Figure 1 is a side elevation of a portion of a laundry press which includes a pressure buck according to the present invention;

Figure 2 is a sectional elevation on the line 2—2 of Figure 3 of the pressure buck shown in Figure 1 but on a scale larger than that of Figure 1;

Figure 3 is a plan of the pressure buck shown in Figure 1 but on a scale larger than that of Figure 1;

Figure 4 is a detail sectional view on the line 4—4 of Figure 3 but on a scale larger than that of Figure 3, and

Figure 5 is a detail sectional view on the line 5—5

5—5 of Figure 3, but on the same scale as that of Figure 4.

Like reference numerals indicate like parts throughout the drawings.

Referring firstly to Figure 1, a portion of the main frame of a laundry press is shown in chain lines at 10 and the lower pressure buck is shown in chain lines at 11. The upper pressure buck is carried on an arm 12 which is pivoted in the frame 10 and is oscillated about its pivot so as to bring the upper pressure buck into and out of co-operative relationship with the buck 11.

The upper pressure buck comprises a wall 13 which, as illustrated, is of cylindrical formation but may be of any other preferred shape. The lower face of this wall 13, as seen in Figure 2, is the pressure-applying face. The upper face of the wall 13 has attached to it a channel-shaped member 14 of corrugated sheet formation which may either be made as a single piece or as a number of separately formed units welded or otherwise secured together. The lateral extremities of the member 14 are continuously welded to the wall 13 at 15 and 16, making tight joints, and the valleys 17 of the member 14 are dimpled at 18 at intervals along their length as clearly seen in Figures 4 and 5. The dimples 18 are perforated so that the valleys 17 may be welded as at 19 through the perforations to the wall 13. Thus between the dimples in any one valley lengths of the latter are spaced away from the wall 13 as shown at 20 in Figure 4, to afford restricted communication between the spaces at each side of the valley.

The corrugations in the member 14 form, with the wall 13, conduits 21 and the ends of these conduits are closed by plates 22 and 23 which are continuously welded at 24 to the member 14 and at 25 to the wall 13, making tight joints.

From the foregoing description it will be seen that the conduits 21 extend from end to end of the wall 13 and are in communication with each other through the spaces 20. To provide for the circulation of steam or other heating medium through the conduits 21, widely spaced branches 26 and 27 are fitted, the former serving for intake and the latter for exhaust. The pipes connected to the branches 26 and 27 will be flexible or jointed to partake of the movement of the buck with its arm 12. On the side of the buck opposite to that at which the branches 26 and 27 are located, is a valve-controlled vent 28 which may be used to permit the exhaust of air, say when starting up the heating of the buck. Any liquid forming in or reaching the conduits 21 will

be able to pass away through the branch 27 when the buck arm 12 swings away into its inoperative position.

The corrugated member 14 being attached to many points to the wall 13 will stiffen the latter in addition to enabling the wall to be heated. Studs 29 are welded or otherwise attached to the member 14 and the end plates 22 and 23 for use in securing a covering sheet to the wall 13.

As illustrated in Figure 1, the upper buck is secured to the arm 12 by a ball-and-socket connection. The socket 30 is welded between two bridge plates 31 and 32 which extend transversely across the corrugated member 14 and are welded at intervals at 33 to the latter. As will be seen from Figure 2, the bridge plates 31 and 32 fit the external contour of the corrugations and reach into the valleys thereof, thus assisting to prevent distortion and ensuring adequate interconnection of the parts. The slotted plate 34 reaching out from the socket 30 co-operates with a pin 35 depending from the arm 12 to prevent undue swinging of the buck about the aforesaid ball-and-socket connection.

It is to be understood that the invention is not restricted to the precise constructional details set forth. For instance, the invention is not limited to being applied to movable pressure bucks. Nor is it essential to weld the various parts of the buck together as other securing means and jointing means may be employed. Moreover instead of dimpling the valleys equivalent spacing washers may be provided which may be welded, riveted or otherwise held in place.

We claim:

1. In a pressure buck for a laundry press, in combination, a wall member one face of which constitutes the work-engaging face of the buck, and means associated with the wall member for stiffening and preventing the distortion thereof and defining, together with said wall member, a steam chamber substantially coextensive in area with said wall member, said means including a corrugated sheet member disposed in spaced relationship to said wall member, plates at the ends of said corrugated member securing together the said members and comprising the end walls of said steam chamber, and elements attaching each valley of the corrugated member to the wall member at a plurality of points.

2. In a pressure buck for a laundry press, in combination, a wall member one face of which constitutes the work-engaging face of the buck, and means associated with the wall member for stiffening and preventing the distortion thereof and defining, together with said wall member, a steam chamber substantially coextensive in area with said wall member, said means including a corrugated sheet member disposed in spaced relationship to said wall member, plates at the ends of said corrugated member securing together the said members and comprising the end

walls of said steam chamber, each valley of the corrugated member being dimpled at a plurality of points along its length, and each such dimple being rigidly attached to the wall member.

3. In a laundry press, a supporting frame, a pressure buck pivotally mounted with respect to said frame for swinging movement about an axis adjacent one side edge of said buck from a substantially horizontal position upwardly to a position in which said pivoted edge is lower than any other portion of the buck, said buck comprising a wall member one face of which constitutes the work-engaging face of the buck, and means associated with the wall member for stiffening and preventing the distortion thereof and defining, together with said wall member, a steam chamber substantially coextensive in area with said wall member, said means including a corrugated sheet member disposed in spaced relationship to said wall member, means at the ends of said corrugated member securing together the said members, means attaching each valley of the corrugated member to the wall member at a plurality of spaced points, whereby flow of fluids from one side of said chamber to the other is substantially unobstructed, and steam connections for said chamber provided at said edge of the buck, whereby drainage of condensate may be quickly and thoroughly effected from all parts of said chamber upon swinging the buck as in the normal use of the press.

4. In a laundry press, a supporting frame, a pressure buck pivotally mounted with respect to said frame for swinging movement about an axis adjacent one side edge of said buck from a substantially horizontal position upwardly to a position in which said pivoted edge is lower than any other portion of the buck, said buck comprising a wall member one face of which constitutes the work-engaging face of the buck, and means associated with the wall member for stiffening and preventing the distortion thereof and defining, together with said wall member, a steam chamber substantially coextensive in area with said wall member, said means including a corrugated sheet member disposed in spaced relationship to said wall member, plates at the ends of said corrugated member securing together the said members and comprising the end walls of said steam chamber, each valley of the corrugated member being dimpled at a plurality of spaced points along its length, and each such dimple being rigidly attached to the wall member, whereby flow of fluids from one side of said chamber to the other is substantially unobstructed, and steam connections for said chamber provided at said edge of the buck, whereby drainage of condensate may be quickly and thoroughly effected from all parts of said chamber upon swinging the buck as in the normal use of the press.
